Sept. 28, 1948.

A. C. BLEVINS

Des. 151,117

BATTERY CHARGING MACHINE OR SIMILAR ARTICLE

Filed July 21, 1947

UNITED STATES PATENT OFFICE

151,117

DESIGN FOR A BATTERY CHARGING MACHINE OR SIMILAR ARTICLE

Albert C. Blevins, Dallas, Tex., assignor to Comet
Battery Charger Company, Ltd., Dallas, Tex.

Application July 21, 1947, Serial No. 140,413

Term of patent 7 years

(Cl. D26—5)

To all whom it may concern:

Be it known that I, Albert C. Blevins, a citizen of the United States, residing at Dallas, in the county of Dallas and State of Texas, have invented a new, original, and ornamental Design for a Battery Charging Machine or Similar Article, of which the following is a specification, reference being had to the accompanying drawing, forming part thereof.

Figure 1 is a side elevational view of a battery charging machine, showing my new design.

Figure 2 is a plan view, and

Figure 3 is a front elevational view showing my new design.

I claim:

The ornamental design for a battery charging machine or similar article, as shown.

ALBERT C. BLEVINS.
